P. DICKSON.

Sled-Brake.

No. 8,903.

Patented Apr. 27, 1852.

UNITED STATES PATENT OFFICE.

PERRY DICKSON, OF BLOOMING VALLEY, PENNSYLVANIA.

HOLDBACK FOR SLEDS.

Specification of Letters Patent No. 8,903, dated April 27, 1852.

To all whom it may concern:

Be it known that I, PERRY DICKSON, of Blooming Valley, in the county of Crawford and State of Pennsylvania, have invented a new and useful Improvement in the Hold-backs of Sleds; and I do hereby declare that the following is a full, clear, and exact description of the same, reference being had to the accompanying drawings, forming part 10 of this specification, in which—

Figure 1, is a plan of a sled to which the improvement is applied. Fig. 2, is a longitudinal elevation of the same. Fig. 3, is a longitudinal section of the same.

15 Similar letters of reference indicate corresponding parts in each of the several figures.

A, is the sled.

B, is the roller which is square, and turns 20 upon pivots b, b, which are placed as far as possible downward and backward from its center.

C, C, are the dogs, which are secured by clamp bolts a, to the upper side of the roller 25 opposite the hounds of the tongue; they are of sufficient length to allow of their ends, which are hooked, to enter the snow or ice, when the roller is turned back far enough to bring them to an angle of 45° to the 30 surface. The front end of each dog has a hinge eye formed upon it which stands above and in front of the roller.

D, is the tongue, to the hounds d, d, of which are secured plates E, E, on the undersides of which are eyes which fit to, and 35 form hinge joints e, with the eyes on the front ends of the dogs. The back parts f, f, of the plates E, extend over the front parts of the dogs, which are upon the roller, and 40 form stops, against which the dogs and roller rest, and are kept rigid with the tongue while drawing.

The operation is as follows—in drawing, the dogs are held up to the position shown in Fig. 2, as the draft acting on the hinges 45 e, turns the roller over forward; but in descending an inclined surface, where the sled has a tendency to run faster than is consistent with safety, the slightest cessation of draft on the part of the animal, will 50 cause the roller to turn over backward and drive the dogs into the ground as represented in Fig. 3. In stopping the sled on a level surface the same effect will be produced by the stopping of the animal; but 55 on the slightest draft being applied to the tongue the dogs are raised and the sled is left free to run onward. In backing, when necessary, the form and position of the teeth of the dogs, allow them to slide freely over 60 the ground.

I do not claim connecting the dogs with, and operating them by the backward pressure of the tongue, but

I claim as my invention and desire to secure by Letters Patent, as being more simple than the ordinary means by which this is effected,

Attaching the dogs C, C, to the roller B, rigidly, instead of to the runners as is usual, 70 and connecting the tongue to the said roller by hinges or analogous joints, in such a manner that the backward motion of the tongue in relation to the body of the sled, turns the roller on its axis and forces the 75 points of the dogs so attached to it into the snow or ice of the road, substantially as and for the purpose herein set forth.

PERRY DICKSON.
